US00D878662S

(12) **United States Design Patent** (10) **Patent No.:** **US D878,662 S**
(45) **Date of Patent:** **** Mar. 17, 2020**

(54) **LIGHTING FIXTURE**

(71) Applicant: **SWAROVSKI LIGHTING, LTD.**,
Plattsburgh, NY (US)

(72) Inventors: **Andrew Schuyler**, Colchester, VT
(US); **Chad Recore**, Peru, NY (US);
Gaetano Ling, Palo Alto, CA (US);
Elger Oberwelz, San Francisco, CA
(US); **Courtney Song**, Saratoga, CA
(US); **Tobias Toft**, San Francisco, CA
(US); **Aaron Wansch**, San Francisco,
CA (US); **Brian Wong**, San Francisco,
CA (US)

(73) Assignee: **Swarovski Lighting, Ltd.**, Plattsburgh,
NY (US)

(**) Term: **15 Years**

(21) Appl. No.: **35/001,501**

(22) Filed: **Feb. 23, 2018**

(80) **Hague Agreement Data**

Int. Filing Date: **Feb. 23, 2018**

Int. Reg. No.: **DM/100884**

Int. Reg. Date: **Feb. 23, 2018**

Int. Reg. Pub. Date: **May 11, 2018**

(51) **LOC (12) Cl.** **26-05**

(52) **U.S. Cl.**

USPC **D26/88**

(57) **CLAIM**

The ornamental design for a lighting fixture, as shown and described.

DESCRIPTION

Lighting fixture

1.1 Perspective

1.2 Front

1.3 Back

1.4 Top

1.5 Bottom

1.6 Left

1.7 Right

(Continued)

The broken lines in the drawings illustrate portions of the lighting fixture which form no part of the claimed design.
